UNITED STATES PATENT OFFICE

2,007,826

SOD EDGING TOOL

Jesse Fickes, Cuyahoga Falls, Ohio

Application March 19, 1934, Serial No. 716,257

5 Claims. (Cl. 97—227)

This invention relates to apparatus for trimming sod along the edges of lawns and other sodded areas and is particularly adapted for use in cutting the edges of lawns on an even line extending in spaced relation to the curb, side walk, drive or the like.

Objects of the invention are to provide a sod trimming tool of simple, durable construction, which can be manufactured at a low cost, which can be conveniently operated and which will be very efficient in use.

Other objects are to provide a tool of the character above indicated having a frame of simple construction and an adjustable, weighted sod cutting knife mounted for sliding movement therein and horizontal adjustable means for engaging the edge of a side walk or other element to accurately position the sod cutting knife in spaced relation thereto.

20. The above objects are accomplished and additional ends are attained by the novel construction, combination and arrangement of parts hereinafter described and illustrated in the accompanying drawing wherein I have shown a preferred form of the invention, it being understood that changes and modifications may be made or resort had to substitutions which come within the scope of the claims hereunto appended.

30. In the drawing like characters of reference are used to designate like parts as the same may appear in each of the several views and in which:

Figure 1 is a perspective view of a sod cutting device constructed in accordance with this invention.

Figure 2 is a vertical, sectional view of same taken as indicated by the lines 2—2 of Figure 1.

Figure 3 is a vertical, sectional view taken as indicated by the lines 3—3 of Figure 1.

40. Figure 4 is a vertical, sectional view taken as indicated by the lines 4—4 of Figure 1.

Proceeding now to a detailed description of the invention with reference to the particular adaptation thereof disclosed in the drawing, there is shown a frame composed of a single piece of steel rod, bent to form the horizontal base portions 5 and 6 which are positioned in parallel relation to each other. The rod is bent upwardly from the portions 5 and 6 to form the side members 7 and 8 which are disposed in parallel spaced relation to each other.

The rod is bent back at the upper end of each side member 7 and 8 to form the horizontal portions 9 and 10 which are disposed in parallel relation to the portions 5 and 6. The

portions 9 and 10 are connected by a horizontal handle member 11.

The rod is bent at a right angle at the other end of the portion 5 to form a horizontal portion 12 and is likewise bent at the other end of the portion 6 to form a horizontal portion 13. The portions 12 and 13 are disposed in parallel relation to the handle 11. While the portions 12 and 13 are in axial alignment, the rod 13 is turned outwardly at the inner end of said portions to form the horizontal ends 14 and 15 which are disposed in parallel relation to each other.

The numeral 16 denotes a step which is of sheet metal positioned on the portions 14 and 15 with the ends of the metal turned under to form a tubular loop 17 at each lateral side thereof. The ends of the strip 19 are continued inwardly from the loop 17 in parallel relation to the upper face of the step 16 and the said ends 19 are secured to the main body of the step 16 by the screw bolts 18 which are entered through suitable bores in the step 16 and are operated in threaded bores in the end portions 19.

The portions 14 and 15 are entered in the loop 17 and are secured therein by operating the screws 18. The step 16 is provided along the inner edge thereof with a downwardly turned tongue 21 which as shown in the drawing is bifurcated to form the prongs 22 and 23.

The numeral 24 denotes a horizontally positioned, rectangular weight which is provided on each end thereof with a plate 25. The plates 25 are secured to the weight 24 by means of the screws 26 or any suitable fastening means. Each plate 25 is provided at the upper edge thereof with a tubular extension 27 and each tube 27 is provided with a vertical bore 28 in which is received the side members 7 and 8.

The weight 24 is provided with parallel, spaced bores 29 and 30 to receive the lower ends of the handle member 31. The handle member 31 is composed of a single piece of steel rod having a horizontal handle piece and having side members 32 and 33 turned downwardly in parallel, spaced relation with the lower ends thereof projecting through the bores 29 and 30. Each of the members 32 and 33 is provided with an annular flange 34 which engages the upper face of the weight 24 to limit the downward movement of the rods 32 and 33 in the bores 29 and 30 as shown in Figure 2.

The numeral 35 denotes a knife which is in the form of an angle bar having a horizontal portion 36 projecting from the upper edge thereof. The

horizontal portion 36 is provided with bores 37 which are positioned therein to receive the downwardly projecting ends of the rods 32 and 33, when the horizontal portion 36 is positioned flat 5 against the bottom of the weight 24. The lower end portion of each rod 32 and 33 is threaded and the nuts 38 are operatively positioned on the lower ends thereof to firmly secure the handle 31 in position on the weight 24 and to hold the 10 knife 35 in the proper position thereon.

In use, the step 16 is positioned on the sidewalk or similar elevation with the down turned portion 21 engaging the sidewalk and the prongs 22 and 23 are forced downwardly into the earth 15 by engaging the step 16 with the foot. The step 16 is adjusted to space the knife 35 the proper distance from the down turned portion 21. The handle 11 is grasped with one hand and the handle 31 with the other. The handle 31 is then operated to raise the weight 24 whereby it will fall by the force of gravity and by such additional force which may be exerted on the handle 31 to drive the knife in the sod. The handle 31 is then 20 raised, the device lifted by the handle 11 and moved to one side, thus successively repeating the 25 operation to form a clean even cut extending in spaced relation to the edge of the side walk, curb or other element engaged by the downturned portion 21.

30 It will be seen that the knife 31 may be reversed to position it closer to the down-turned portion 21 and that the step 16 may be slid longitudinally on the rods 14 and 15 to adjustably secure the portion 21 in proper, spaced relation 35 to the knife 35.

Having thus illustrated my invention and described the same in detail, what I claim as new and desire to secure by Letters Patent is:—

40 1. A sod trimmer of the character described comprising a frame, means adjustably mounted on the lower portion of said frame to engage a sidewalk or the like, said frame including up-

wardly projecting, parallel side bars, a cross rod connecting said side bars at the upper ends thereof, a weight slidably mounted on said bars and extending therebetween, a handle secured to said weight and projecting upwardly with the upper end thereof positioned in the vicinity of said cross rod, and a knife secured to the lower face of said weight.

2. A sod trimmer of the character described comprising a frame, said frame including upwardly projecting, parallel side bars, a handle connecting said side bars at the upper ends thereof, a weight slidably mounted on said bars and extending therebetween, a handle member secured to said weight and projecting upwardly 10 with the upper end thereof positioned in the vicinity of said first named handle, and a knife secured to the lower face of said weight.

3. A sod trimmer of the character described, including a frame, parallel side members on said frame, a weight slidably mounted on said side members, a knife secured to the lower side of said weight, and a handle for manipulating said weight.

4. A sod trimmer of the character described including a frame, a weight mounted for vertical movement on said frame, a knife secured to the lower side of said weight, a handle for manipulating said weight, and means on said frame for engaging a sidewalk or other element to locate 20 the knife in the proper operative relation thereto.

5. A sod trimmer of the character described, including a frame, a foot plate adjustably mounted thereon and projecting from one side thereof, a guide blade projecting downwardly from one edge of said foot plate, parallel side members on said frame, a weight slidably mounted on said side members, a knife secured to the lower side of said weight, and a handle for manipulating 35 said weight.

40 JESSE FICKES.
